FOLDING TRAVELING CLOCKCASE

Samuel J. Kaufman, New York, N. Y.

Application December 18, 1950, Serial No. 13,491

Term of patent 7 years

(Cl. D42—7)

To all whom it may concern:

Be it known that I, Samuel J. Kaufman, a citizen of the United States, residing at New York city, in the county and State of New York, have invented a new, original, and ornamental Design for a Folding Traveling Clockcase, of which the following is a specification, reference being had to the accompanying drawing, forming a part thereof.

Fig. 1 is a front view of a folding traveling clockcase, showing my new design.

Fig. 2 is a side view thereof.

Fig. 3 is a rear view thereof.

Fig. 4 is a perspective view of my clockcase shown in open position.

The dominant feature of the design resides in the portion shown in full lines.

I claim:

The ornamental design for a folding traveling clockcase, substantially as shown and described.

SAMUEL J. KAUFMAN.
